UNITED STATES PATENT OFFICE.

OTTO HEISLER, OF MILWAUKEE, WISCONSIN.

CLOTHES WRINGER.

Application filed March 14, 1922. Serial No. 543,554.

To all whom it may concern:

Be it known that I, Otto Heisler, a citizen of the United States, and resident of Milwaukee, in the county of Milwaukee and State of Wisconsin, have invented certain new and useful Improvements in Clothes Wringers; and I do hereby declare that the following is a full, clear, and exact description thereof.

10 My invention relates to clothes wringers and its general object is to provide a construction by means of which the clothes are effectively prevented from adhering to the rolls and winding about and becoming entangled with the same.

15 The invention consists further in certain details of construction and combinations thereof, which will be more particularly described in connection with the accompanying drawing and subsequently claimed.

In the drawing,

Figure 1 represents a rear elevational view of a clothes wringer, constructed according to my invention, a part being broken away 25 and shown in section to better illustrate the construction thereof.

Figure 2 is a vertical sectional view taken on the line 2—2 of Figure 1, and

30 Figure 3 is a detail sectional view taken on the line 3—3 of Figure 1.

Referring more particularly to the drawing, the numeral 5 designates a wringer frame, in which are rotatably mounted the rolls 6, the upper roll being journaled in 35 blocks 7 which are slidably mounted in the sides of the frame, and yieldably held in their lowermost position by means of coil springs 8, one of which is used in connection with each journal block. Each of the 40 springs 8 engages at its lower end, an up-standing boss or lug 9, which is secured to the block 7, and at its upper end engages a similar boss formed on the end of bracket 10.

45 Adjusting screws 11 are mounted in threaded connection with bushings 12 which are secured in the upper rail of the wringer frame and at their lower ends engage in recesses 13, formed in the respective brackets 10, whereby the screws may be adjusted to limit the extent of the upward movements of the brackets and thereby adjust the tension of the springs 8.

50 The brackets 10 are secured to and extend outwardly from the ends of a supporting bar 14; which, by reason of the springs 8, has a floating connection with the wringer frame.

Guides 15 are secured to the bar 14 and extend vertically downwardly therefrom, and thus form means for slidably receiving a brush holder 16, in the lower side of which 60 suitable brushes 17 are secured. The movement of the holder 16 downwardly is adjustably limited by means of nuts or bolts 18 and between the holder and the supporting bar 14 these bolts are surrounded by 65 compression springs 19 which urge the brushes downwardly. The nuts on the bolts 18 will normally be adjusted so as to permit the brushes 17 to engage the upper surface of the roll 6 with sufficient force to detach 70 any clothes which may adhere to the roll and having a tendency to wind around the same.

A delivery board 20 is secured to the wringer frame in the usual position in rear of the lowermost roll 6 and sloping downwardly and outwardly to deliver the clothes as they pass thru the rolls. In order to prevent any possibility of the clothes winding about the lower roll, a shoe 21 is provided with pins 22, which are reciprocably mounted in bushings 23 secured in the board 20 and suitable compression springs 24 are inserted in sockets 25 formed in the board and shoe. These springs hold the shoe constantly 80 in contact with the lower roll and the face 85 of the shoe is preferably formed concave so as to closely engage the roll and to prevent any clothes winding therearound.

From the foregoing description, it will be 90 seen that I have provided a simple and practical construction which will effectively prevent the clothes from being wound around the rolls and will cause the same to be properly delivered into the basket which will be placed underneath the delivery board.

95 Although I have shown and described specifically one construction by means of which the invention may be carried out, it will also be understood that many minor changes may be made in the form and proportions of the several parts without departing from the spirit or sacrificing any of the advantages of the invention which is defined by the claims hereunto appended.

100 I claim:

1. In a wringer, a pair of rolls between which the clothes are fed, a vertically adjustable bar disposed thereabove, vertical guides depending from said bar, a brush holder slidably mounted in the guides and having brushes normally in contact with the upper roll, means for resiliently urging the 110

brush and holder downwardly and means for adjustably limiting the downward movement thereof.

2. In a wringer, a pair of rolls between which the clothes are fed, a frame in which the rolls are journalled, a delivery board secured to the frame behind the lower roll and sloping outwardly and downwardly, a shoe adapted to engage the roll and having

supporting pins slidably mounted in said board, and means resiliently urging the shoe into contact with the roll to strip the clothes therefrom.

In testimony that I claim the foregoing I have hereunto set my hand at Milwaukee, in the county of Milwaukee and State of Wisconsin.

OTTO HEISLER.
